BOTTLE CLOSURE

James A. Murdock, Chicago, Ill.

Application February 12, 1940, Serial No. 318,464

3 Claims. (Cl. 215—63)

This invention relates to closures for bottles and similar containers and is especially useful in cases where the bottles contain gaseous liquids, such as carbonated beverages, which must be confined under pressure.

The object of the invention is to provide an improved bottle closure which is simple in construction and operation, and economical to manufacture.

10 A further object of the invention is to provide a bottle closure which is readily and securely applied to a bottle and can be readily removed therefrom without tools or the manipulation of parts.

15 A further object of the invention is to provide a bottle closure which may be opened or closed easily by the use of the same hand which holds the bottle, thus leaving the operator's other hand free.

20 A further object of the invention is to provide a bottle closure in which the means by which the stopper is held to the neck of the container is tightened simultaneously with the clamping shut of the stopper over the mouth of the bottle, thus requiring a minimum of motion and of effort on 25 the part of the user.

25 A further object of the invention is to provide a bottle closure which will fit tightly to the opening and the mouth of the bottle, and yet will be readily removable and easily transferable from 30 one bottle to another of the same type, without damage to either the bottle or the closure, and regardless of minor variations in the outer diameter of the mouths of the bottles.

35 A further object of the invention is to provide a bottle closure which is so associated with the bottle when in use as to prevent the closure from becoming misplaced when the bottle is opened and the contents are being dispensed therefrom.

40 A further object of the invention is to provide a gas-, air-, and liquid-tight bottle closure to take the place of the usual original closure after such original closure has been removed.

45 Other objects, advantages, and capabilities of the invention will appear from the following description of a preferred embodiment thereof, taken in conjunction with the accompanying drawing in which:

Figure 1 is a perspective view of the closure in closed position upon the bottle.

50 Fig. 2 is a perspective view of the closure in open position upon the bottle.

Fig. 3 is a plan view of the underside of the closure cap, shown in open relation with respect to the retainer ring by which the closure is held 55 upon the bottle.

Fig. 4 is a horizontal sectional view of the closure taken substantially on the line 4—4 of Fig. 1.

Fig. 5 is a sectional view through the closure cap taken on the line 5—5 of Fig. 2, and showing a plan view of the retainer ring about the neck 6

of a bottle.

Fig. 6 is a fragmentary sectional view taken on the line 6—6 of Fig. 4, showing the manner in which the cap is held in closed position by the retainer ring.

Fig. 7 is a plan view of the blank of the bottle closure cap before it is formed into the completed structure.

Similar numerals refer to similar parts throughout the several views.

Referring to the drawing, the reference numeral 11 designates the conventional bottle of which a fragment is shown. The bottle shown is of familiar form, with a cylindrical body tapering at 12 to an annular shoulder 13, above which 14 is the narrow neck 14 surmounted by the annular lip 15 about the mouth 16 of the bottle. The bottle shown and described herein is a conventional beverage bottle, such as is commonly used to contain carbonated beverages. These bottles are commonly sealed with a so-called "crown cap," which is a metal cap crimped over the lip 15 and carries a circular cork insert within the cap which is pressed between the top of the cap and the top of the bottle lip 15 and over the bottle 20 mouth 16.

While the invention has been shown and described as applied to a bottle, it is designed to be readily applicable to containers of any kind which terminate in a tubular mouth with an annular lip at the mouth or near thereto to serve as an abutment for the retaining ring by which the closure may be secured to the bottle. Obviously, the lip need not completely encircle the throat of the container, and the closure will operate equally well upon containers having multiple studs or other abutments about the neck.

The closure shown in preferred form, consists of a retainer ring 20, made of flexible resilient metal. The ring 20 is interrupted at the back, 45 each of the ends of the wire being carried rearwardly at the plane of the ring into the horizontal extensions 21, each of which is then bent inwardly at the same plane as at 22. The ends each terminate in a vertical section 23, bent upwardly 50 and substantially perpendicular to the horizontal sections 21 and 22.

Diametrically opposite the interrupted section of the retainer ring, the ring 20 is bent to form the shoulder 24, which is shown as formed by 55

forming a short length of the wire into a straight section. The shoulder may also be formed by securing a shoulder to the ring 20, by welding, crimping, etc.

5. The ends 21—22—23 of the ring 20 are passed through a pair of vertical ears 33, bent from the sheet metal cap 26.

This cap 26, best shown in Fig. 1, is pressed from a blank of light sheet metal (Fig. 7) into the form shown. This cap has a body generally circular in form, perforated at the center 25 to receive a stud 41 formed integrally with the circular sealing member 40, which is more fully described below.

15. The side edges of the body of the cap 26 may be flanged to form walls 27 to confine the sealing member 40, so that any compression thereof will not force the sealing member from beneath the cap.

20. The front of the cap 26 is formed from a long tongue, bent as indicated by the dotted lines in Fig. 7. The tongue rises from the cap into an abrupt vertical bow 28, then is bent downwardly and inwardly to clasp the bottle, and terminates 25 in the outwardly projecting fingerpiece 30. Intermediate the end of the tongue and the bow 28, the tongue is cut at 29 and the metal pressed inwardly to form the two detents 29 which are designed to catch beneath the shoulder 24.

30. The rear end of the cap blank is formed into the horizontal bow 31, which terminates in a horizontal plate 32, of which the lower surface is shown in Fig. 3 and the upper surface in Fig. 4. The perforated ears 33, are formed by bending the blank down and perpendicular to the plate 32. The plate 32 is cut away at its inner end to form the notch 34. The edges of the plate 32 are rounded to form the cam surfaces 35, between which the ends 23 of the ring 20 swing into the notch 34.

40. The perforated ears 33 receive the straight horizontal sections 22 of the ring 20 which form pivots for the cap.

45. As heretofore stated, the central body of the cap is perforated to receive the stud 41 by which the circular sealing member 40 is held within the cap. The seal 40 is made of cork or preferably rubber or similar compressible material, and is cut into the form shown. The seal is preferably formed with a bevel 42 about the center so that its central portion is thicker than the edges.

Operation of the bottle closure

With the closure in open position as shown in Figs. 2 and 5, the ends 23 of the retainer ring 55 20 are free of the cams 35. The ring will then expand when pressed over the lip 15 of the bottle. With the cap in this position, the closure can thus be applied to a bottle merely by pressing the ring 20 over the lip about the bottle mouth, 60 and the closure can be removed by lifting the assembled closure so that the ring expands and passes over the bottle lip.

If the ring is pressed over the bottle lip, it will, because of its resilience, snugly embrace the bottle neck 14. If the cap 26 is now pressed with the thumb or forefinger of the same hand by which the bottle is held, the cap 26 will swing about the pivots 22—33 and the fingerpiece of the tongue on the opposed side of the cap will 70 slide over the shoulder 24 until the detents 29 engage the shoulder. As the cap is pressed, the

resilience of the cap member, due to the bows 28 and 31, will permit these detents 29 to ride over the shoulder 24 and snap into engagement with the lower edge thereof. The closure will then be applied to the bottle as shown in Fig. 1. 5

As the cap is swung down, the notch 34 swings over the ends 23 of the retainer ring 20 and the cammed edges 35 of the notch 34 press the ring ends toward each other, thus shortening the ring and tightening it about the bottle neck 14, 10 simultaneously with the closing of the cap and the locking of it in closed position. As soon as the cap is latched down by the engagement of the detents 29 with the shoulder 24, the cams 35 lock the ring ends 23 in final position and thus 15 lock the retainer ring to the bottle neck and the closure to the bottle mouth.

As the cap is pressed down, the compressible seal 40 enters the bottle mouth 16 and comes into contact with the lip 15 throughout its circumference to form a tight seal against liquids and gases contained in the bottle. The resilience of the seal tends to force the cap from the bottle and increases the pressure of the detents 29 against the lower surface of the shoulder 24, 25 and correspondingly tightens the grip of the cap upon the bottle.

If the bottle is to be opened, the thumb of the same hand by which the bottle is held can be inserted under the fingerpiece 30, and the 30 fingerpiece thus lifted until the detents 29 are free of the shoulder 24, whereupon the resilience of the cap member and the seal 40 together with the resilience of the wire forming the ring ends 23 against the cams 35 will quickly swing 35 the cap into the position shown in Fig. 5, and the resilience of the wire ring 20, imparted to the ends 23 riding on the cams 35, will hold the cap in open position while the contents of the bottle are being poured. If the bottle is emptied, the 40 closure can be readily removed by lifting the retainer ring 20 over the lip 15 of the bottle.

It is to be observed that each of these operations can be performed with one hand.

Although the invention has been disclosed in 45 connection with the specific details of preferred embodiments thereof, it is to be understood that such details are not intended to be limitative of the invention except insofar as set forth in the accompanying claims.

Having described my invention what I claim as new and desire to secure by Letters Patent is:

1. A closure for containers comprising a removable ring to encircle the container near the mouth thereof, a cap pivoted to the ring, and 55 cams upon said cap to tighten the ring about the container when the cap is swung into closed position.

2. A container closure of the character described comprising a broken retainer ring to 60 encircle the container, a cap pivoted to the ring, and cams upon the cap to force the ends of the ring together and shorten the ring as the cap is closed.

3. A closure for containers comprising a removable ring to encircle the container near the mouth thereof, a cap pivoted to the ring, and 65 cams upon said cap to lock the ring about the container when the cap is swung into closed position.

70 JAMES A. MURDOCK.
